CLAIM

We claim the ornamental design for a utility task vehicle cargo rack, as shown and described.

DESCRIPTION

FIG. 1 is a partial perspective view of a utility task vehicle having a utility task vehicle cargo rack according to our new design mounted thereon.

FIG. 2 is a top-rear perspective view of the utility task vehicle cargo rack according to our new design.

FIG. 3 is a bottom-front perspective view thereof.

FIG. 4 is a top plan view thereof.

FIG. 5 is a bottom plan view thereof.

FIG. 6 is a left-side elevation view thereof.

FIG. 7 is a right-side elevation view thereof.

FIG. 8 is a rear elevation view thereof; and,

FIG. 9 is a front elevation view thereof.

Broken lines illustrate the utility task vehicle and portions of the utility task vehicle cargo rack that form no part of the claimed design.
